UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

PICOT EDGING FOR FABRICS.

1,378,270.

Specification of Letters Patent. Patented May 17, 1921.

Application filed April 20, 1916. Serial No. 92,454.

To all whom it may concern:

Be it known that I, LANSING ONDERDONK, a citizen of the United States, residing at New York, in the county of New York, 5 State of New York, have invented certain new and useful Improvements in Picot Edgings for Fabrics, of which the following is a description, reference being had to the accompanying drawing and to the 10 figures of reference marked thereon.

The invention relates to new and useful improvements in edgings for fabrics, and more particularly to a picot edging, that is an edging wherein there are at intervals 15 spaced projecting loops.

An object of the invention is to provide a machine-constructed picot edging, that is, an edging for fabrics wherein the over-edge stitches are formed with a series of 20 spaced loops which project laterally beyond certain of the over-edge stitches and the edge of the fabric.

A further object of the invention is to provide a picot edging of the above character 25 wherein one of the stitching threads is formed into loops which project laterally beyond certain of the over-edge stitches and the edge of the fabric.

These and other objects will in part be 30 obvious and will in part be hereinafter more fully described.

In the drawings:

Figure 1 is a view in plan showing a fabric having my improved picot edging applied thereto, and also showing the method of making the same;

Fig. 2 is a bottom plan view of the fabric with the edging applied thereto;

Fig. 3 is a diagrammatic view showing 40 the two-thread overseaming stitches of Figs. 1 and 2 and the relation of the same to the fabric;

Fig. 4 is a similar view, showing the 45 needle loop extended or enlarged and projecting from the edge of the fabric;

Fig. 5 is a view, similar to Fig. 1, but 50 showing a slightly modified form of the invention wherein the projecting loops are formed from the looper thread instead of the needle thread;

Fig. 6 is a diagrammatic view showing the looper thread loop enlarged or extended to project beyond the edge of the fabric;

Fig. 7 is a detail in section showing the 55 edging of Fig. 1 applied to a fabric wherein the edge of the fabric is folded back within the limits of the overseaming stitches;

Fig. 8 is a view, similar to Fig. 1, but showing a slightly modified form of the 60 invention wherein two looper threads as well as a needle thread are used for forming the edging, and one of the looper threads is formed with loops projecting beyond the edge of the fabric;

Fig. 9 is a diagrammatic view of the 65 edging and fabric shown in Fig. 8, showing the relation of the threads to the fabric; and

Fig. 10 is a view, similar to Fig. 9, but showing a slightly modified form in the 70 arrangement of the loops.

The invention consists broadly in a machine-constructed picot edging that is, an 75 edging wherein certain of the threads are formed into enlarged loops which are so disposed as to project laterally from the other loops of the overseaming stitches and laterally from the edge of the fabric and in the plane of the fabric. This edging may be constructed from two-thread or three-thread 80 overseaming stitches and either the needle thread or one of the looper threads may be formed into loops which project beyond the edge of the fabric so as to produce this picot 85 edging. The edge of the fabric may also be folded back within the limits of the overseaming stitches, if desired, so that the overseaming stitches will inclose the folded edge of the fabric.

Referring more in detail to Figs. 1 to 4, 90 inclusive, of the drawings, my improved picot edging consists of two threads, a needle thread 1 and a looper thread 2. A fabric, indicated at F, has the edging formed thereon. The needle thread is formed into 95 loops 3 which are passed down through the fabric at the points 4, and these needle loops are carried to the edge of the fabric. The looper thread is formed into loops 5 which pass through the respective loops 100

formed in the needle threads. These looper thread loops are laid on the upper face of the fabric, and the needle thread loop passes down through the looper thread loop. 5 This is a well-known form of two-thread over-edge seam and will not need further description.

In Fig. 1 of the drawings, I have shown the needle at N, the threaded looper at L, 10 and the spreader for spreading the needle loop at S. Coöperating with the needle, looper and spreader is a loop retainer R. This loop retainer is timed so as to engage a needle thread loop at every third stitch or 15 puncture of the fabric by the needle. This retainer holds the needle thread loop when the stitch is being set, so that the resultant loop is enlarged or extended, as clearly shown at 6 in Fig. 1. These enlarged or 20 extended loops 6 project beyond the other overseaming stitches and the edge of the fabric and lie in the plane of the fabric, as shown diagrammatically in Fig. 4.

I have produced an edging, therefore, 25 wherein the overseaming stitches encircle the edge of the fabric and at intervals of every three stitches, as shown in Fig. 1, the needle loop is enlarged and extended and projects from the edge of the fabric, thus 30 forming the picot edging. While I have shown in Fig. 1 the loops projecting from the edge of the fabric at every third stitch, it will be understood that this spacing of 35 the loops may be varied without departing from the spirit of the invention.

In Fig. 5 of the drawings, I have shown a two-thread overseam of the character described in connection with Figs. 1 to 4, inclusive. In this showing of the invention, 40 however, the retainer R engages the looper thread between the loops which are projected through the needle thread loops and holds the thread, out so as to form a projecting loop in the looper thread. The projecting loops are indicated at 7 in Fig. 5 45 of the drawings. These loops are shown as being formed at every third stitch or puncture of the fabric by the needle, but it is obvious that they may be spaced any 50 desired number of stitches or needle punctures. This may be accomplished by varying the timing of the movement of the retainer.

In Fig. 6 of the drawings, I have shown 55 diagrammatically the arrangement of threads shown in Fig. 5, and it will be apparent that the projecting loops 7 lie in the plane of the fabric.

In Fig. 7 of the drawings, I have shown 60 a slightly modified form of the invention illustrated in Figs. 1 to 4, inclusive, in that the edge of the fabric is folded back at F'. This folding back of the edge of the fabric is within the limits of the overseaming 65 stitches, and the overseaming stitches en-

tirely encircle the folded edge of the fabric. It will be understood that the fabric may be folded or not, as desired, and the folded edge may be used in connection with any of the forms of the picot edging described. 70

In Fig. 8 of the drawings, I have shown a slightly modified form of the invention in that the overseaming stitches are formed from three threads. The needle thread is indicated at 1. This needle thread is 75 formed into a series of loops 3 which are passed through the fabric. On the underside of the fabric a looper thread 8 is formed into a series of loops which are passed through the respective needle loops 3 and these loops 8 are brought to the edge 80 of the fabric where the looper thread 2 is formed into a series of loops, each of which is passed through a loop in the looper thread 8, and the looper thread 2 is laid on the upper face of the fabric and secured by the needle thread as described in connection with Fig. 1. In this form of the invention shown in Fig. 8, in place of the spreader, a thread carrying looper L' is 90 used and the retainer is timed so as to engage the looper thread, of this looper L'. The retainer enlarges or extends the loops into projecting loops 9 which are shown as spaced three stitches or three needle 95 punctures apart. This spacing of the loops may be varied, as above stated.

In Fig. 10 of the drawings, I have shown an edging having picot loops formed which is similar to that shown in Figs. 8 and 9, with the exception that the tension on the threads have been changed so that the needle loops are drawn to the edge of the fabric and the thread having the picot loops formed therein lies wholly along the 105 edge of the fabric.

It will also be understood that the other looper thread, as in the two-thread stitch, may be extended, if desired, to form the projecting loops. 110

From the above, it will be apparent that I have provided a picot edging which may be made by a sewing machine, and wherein one of the stitching threads of the over-edge stitches is formed into loops which 115 are extended or enlarged so as to project laterally from the edge of the fabric and lie in the plane of the fabric. These loops are spaced so as to give the appearance of the well-known picot edging. 120

By making the picot loops from the needle threads which form the overseaming stitches, said loops are locked so that one loop does not draw thread from the next adjacent loop if a strain is placed thereon, 125 that is to say that the thread between the loops is interlocked or concatenated with the stitches intervening between the picot loops, and this holds the picot loops at a pre-determined size. 130

Having thus described the invention, what is claimed as new is:—

The combination of a fabric and a picot edging therefor, consisting of a needle thread formed into a series of loops extending through the fabric, a looper thread formed into a series of loops extending through the needle thread loops and over the edge of the fabric where said looper thread loops are entered by the needle loops prior to the passing of the same through

the fabric, one of said threads being formed into loops projecting laterally beyond the edge of the fabric, said last named loops being spaced two or more thread concatenations apart. 15

In testimony whereof I affix my signature, in the presence of two witnesses.

LANSING ONDERDONK.
